UNITED STATES PATENT OFFICE.

HERMAN G. REIBEL, OF WARREN, OHIO, ASSIGNOR TO THE PEERLESS ELECTRIC COMPANY, OF WARREN, OHIO, A CORPORATION OF OHIO.

DRIVING CONNECTION FOR MOTOR-DRIVEN FANS OR THE LIKE.

Application filed January 6, 1925. Serial No. 930.

The invention relates to automatically releasable driving connections and particularly to such as are used in connection with the oscillating mechanisms of electric fans.

5 Briefly stated, an important aim of the invention is to provide a drive gearing structure as characterized, which may be rendered temporarily inoperative at will, novel means being employed for doing this and 10 holding the parts against looseness in a desired out of engagement relationship; and which is also provided with a novel torque load responsive means for breaking the drive connection when the load becomes excessive.

A further object of the invention is to provide an automatically releasable driving connection for fans or the like which is simple to adjust, reliable in use, and cheap to 20 manufacture.

Other objects and advantages will be apparent during the course of the following description.

In the accompanying drawings forming 25 a part of this application and in which like numerals are employed to designate like parts throughout the same,

Figure 1 is a side elevation of a fan equipped with the improved oscillating 30 mechanism;

Fig. 2 is a detail horizontal sectional view taken on line 2—2 of Fig. 1;

Fig. 3 is a group perspective illustrating 35 a shaft and means for manually adjusting the shaft vertically;

Fig. 4 is a vertical sectional view through the oscillating mechanism in its inoperative position;

Fig. 5 is a vertical sectional view through 40 the oscillating mechanism in its operative or fan oscillating position;

Fig. 6 is an edge elevation of a slightly modified form of worm wheel.

In the drawings, the numeral 5 designates 45 a base having means whereby the same may be secured to a vertical or horizontal support and as illustrated in Fig. 1 a motor 6 is hingedly connected to the base as indicated at 7. The hinge member 7 is pro-

50 vided with a wing nut 8 to hold the motor 6 in an adjusted position with respect to the axis of the hinge member 7.

The motor 6 is provided with the usual armature shaft 10 on the forward end of 55 which the fan blades 11 are mounted. A

guard 12 of any style is carried by the housing of the electric motor and encloses the blades 11.

Fig. 1 illustrates that the oscillating mechanism is arranged at the rear side of the fan and is provided with a hood or shell 16 into which the rear end of the armature shaft 10 extends. Particular attention is directed to Fig. 2 which illustrates that a driving member in the nature of a worm 18 is secured on the extended rear end of the armature shaft 10 and is constantly in mesh with a worm wheel 19.

The worm wheel 19 is mounted for free rotary movement on a vertically movable 70 shaft 20 and is held in proper position with respect to the worm 18 by a bearing 22. Figs. 4 and 5 plainly illustrate this arrangement.

The opposite sides of the worm wheel 19 75 are provided with annular shoulders 24, the upper shoulder being provided with oppositely located semi-circular recesses 26 for the reception of the end portions of a driving pin or key 28. The driving key or pin 28 is extended transversely through the shaft 20 and when positioned in the recesses 26 a driving connection is established between the worm wheel 19 and the shaft 20.

If desired the recesses in the upper shoulder 24 may be V-shaped as indicated at 29 in Fig. 6. When the end portions of the pin 28 are received in either the recesses 26 or 80 29 as the case may be a driving connection is established between the parts of the oscillating mechanism, but in case the fan strikes an obstruction the connection is such that the pin will leave the recesses and ride over the shoulder 24.

The pin 28 is urged downwardly into the 85 recesses by a spring 32 mounted on the shaft 20 and confined between a shoulder 33 and a thrust bearing 35. The thrust bearing is positioned in a boss 36 on a screw cap 37. It is believed to be obvious that the spring 32 will exert a constant tension endwise on the shaft to urge the terminal portions of the pin 28 into the recesses 26.

In carrying out the invention the upper portion of the shaft 20 is extended through an opening in the boss 36 and is screw threaded for engagement with a knurled nut 40. The knurled nut forms a means whereby the shaft 20 may be manually raised or lowered during the operation of 105 110

the fan for breaking or establishing a driving connection between the pin 28 and the worm wheel 19.

- Particular attention is directed to the fact that the knurled nut 40 is located at the rear side of the fan so that an operator may adjust the oscillating mechanism during the operation of the fan and without possibility of accidentally coming in contact with the blades of the fan. This is an important factor as it entirely removes the element of danger from the adjustment of the fan and persons having no mechanical knowledge whatever may adjust the fan without fear.
- The lower portion of the shaft 20 is provided with a gear 44 in constant mesh with a somewhat larger gear 45 on the upper end of a driven shaft 46. The driven shaft 46 is rotatably extended through the bearing or hub 47 of a cap 48. Of course, the hub member 47 may be bushed with bronze or the like without in any way departing from the spirit of the invention and the scope of what is claimed.

- The lower portion of the shaft 46 carries a disk 50 having an eccentrically located pin 51 to which a link 52 is connected. The link 52 has connection with a relatively fixed portion of the fan so that when the disk 50 is turned the motor and the blades carried thereby will be oscillated.

In the operation of the improved oscillating mechanism the armature shaft, of course, constantly rotates in the same direction and the worm wheel 19 partakes of a similar movement. When the parts are positioned as illustrated in Fig. 5 the rotation of the wheel 19 is transmitted to the shaft 20 so that the disk 50 is turned to bring about the oscillation of the fan.

If the oscillating feature is in operation and the guard on the fan strikes an obstruction the resistance encountered will overcome the tension of the spring 32 and the pin 28 will ride out of the recesses 26 and over the upper shoulder 24. Of course, each time the pin 28 returns to the recesses 26 it will drop into the same and again ride out of these recesses. This will continue until the obstruction which is preventing the fan from oscillating is removed.

The periodical dropping of the pin 28 into the recesses 26 will probably cause a well defined, but not objectionably loud noise which will apprise a person near the fan of the fact that the fan is not permitted to oscillate because of the obstruction.

Having thus described the invention, what is claimed is:—

1. In an oscillating mechanism for fans, a driving member and a driven member, one of said members having a surface recess and the other member having a key designed to engage in said recess to establish a driving connection between said members, bearings

for said members, means for moving one of said members to disengage said recess and key, a spring interposed between said last mentioned member and its bearing for yieldably holding said key and recess in engagement, and means including said spring for holding said member in a plurality of fixed positions wherein said key and recess will be out of engagement.

2. In an oscillating mechanism for fans, a driving member and a driven member, one of said members having a surface recess and the other member having a key designed to engage in said recess to establish a driving connection between said members, bearings for said members, screw means for moving one of said members to disengage said recess and key, a spring interposed between said last mentioned member and its bearing for yieldably holding said key and recess in engagement, and said spring and screw means cooperating to variably position said member to maintain said key and recess out of engagement.

3. An oscillating mechanism for fans comprising a gear case, a constantly driven gear therein, and having a surface recess in one face, an axially movable shaft journaled in said gear case and having a projection designed to engage said recess, said gear being loosely journaled upon said shaft, a spring interposed between said gear case and a shoulder of said shaft for urging the same in a direction to engage said projection with said recess, and means engaging said shaft and said gear case and being operable to actuate and maintain said shaft in a position to hold said projection and recess out of engagement.

4. An oscillating mechanism for fans comprising a gear case, a constantly driven gear therein, and having a surface recess in one face, an axially movable shaft journaled in said gear case and having a projection designed to engage said recess, said gear being loosely journaled upon said shaft, a spring interposed between said gear case and a shoulder of said shaft for urging the same in a direction to engage said projection with said recess, the end of said shaft projecting through said gear case and being threaded, and a nut upon the threaded end of said shaft and engaging said gear case whereby to move said shaft in an axial direction against the tension of said spring to disengage said projection and recess.

5. In an oscillating mechanism for fans, a driving member and a driven member, one of said members having a surface recess and the other member having a key designed to engage in said recess to establish a driving connection between said members, bearings for said members, a screw carried by one of said members and projecting beyond one bearing, yielding means acting upon said

screw-carrying member for normally maintaining the two members in operative engagement and a nut threaded on said screw and engaging said bearing to thereby move
5 said member bodily in an axial direction on rotation of said nut to disengage said recess and key, and cooperating with said yielding means to maintain said screw-carrying member in a plurality of positions out of
10 engagement with said other member.

6. In an oscillating mechanism for fans, a driving member and a driven member, one of said members having a surface recess and the other member having a key designed to

engage in said recess to establish a driving 15 connection between said members, bearings for said members, means for moving one of said members to disengage said recess and key, yielding means acting on one of said members to maintain it in operative engagement with the other member, and means including said yielding means for maintaining said last named member in a plurality of fixed positions wherein said key and recess will be out of engagement. 20 25

In testimony whereof I affix my signature.

HERMAN G. REIBEL.
